PULP SCREENING MACHINE

Nelson Moore Knight, Weymouth Heights, Mass.

Application October 29, 1934, Serial No. 750,481

10 Claims. (Cl. 92—34)

This invention relates to pulp screening machines and it has for its general object to provide an improved pulp screening machine which is constructed to facilitate the screening operation, 5 and for another object to provide a novel pulp screening machine which is constructed so that the screening operation can be performed with the expenditure of a relatively small amount of power for operating the machine.

10 My improved pulp screening machine is provided with a vat or casing having an inlet in its top through which the pulp to be screened is delivered to the vat, and a discharge opening in its lower end through which the screened pulp is discharged, and a screening element having vertical screening walls situated between the inlet and discharge opening. The device also is provided with means for causing the pulp to be forced back and forth through the screening walls during its 20 flow from the inlet to the discharge opening, and with cleaning runners situated closely adjacent the inlet side of the screening walls, together with means for producing a relative motion between said runners and said walls whereby the runners 25 assist in keeping the screening walls free from accumulating deposits of refuse or other material which is screened from the pulp.

In order to give an understanding of the invention I have illustrated in the drawings a selected embodiment thereof which will now be described after which the novel features will be pointed out in the appended claims.

Fig. 1 is a vertical sectional view through a pulp screening device embodying my invention.

35 Fig. 2 is a section on the line 2—2 Fig. 1.

Fig. 3 is a view showing the cleaning runners removed from the screen.

Fig. 4 is a view similar to Fig. 1 but showing a different embodiment of the invention.

40 Fig. 5 is a section on the line 5—5 Fig. 4.

Fig. 6 is a section on the line 6—6 Fig. 4.

Fig. 7 is a fragmentary section on the line 7—7

Fig. 2.

Fig. 8 is a side view of a screening device embodying the invention.

Referring first to the construction shown in Figs. 1, 2 and 3, 1 indicates generally a casing which contains the pulp screening element and through which the pulp flows during the screening operation. This casing is shown as cylindrical in shape with its axis extending vertically.

50 The casing comprises an upper head 2 provided with a pulp inlet 3 through which the pulp to be screened is delivered to the casing, and a lower head 4 having the discharge opening 5 through

which the screened pulp is discharged from the casing. The side wall of the casing is formed by two oppositely-disposed supporting members 6 which are secured at their lower ends to the lower head 4 and at their upper ends to the upper head 2, and two curved plates 7 which are connected at their vertical edges to the supporting members 6. Each supporting member 6 is formed with an outwardly-extending flange 8 at each edge thereof, and each plate 7 has secured to each vertical edge an angle iron member 9. The radial leg of each angle iron 9 is bolted to the radial flange 8 of the adjacent supporting member 6 by means of suitable bolts 10, and the members 6, which are slightly curved as shown in Fig. 2, together with the plates 7 form the side walls of the casing 1. The upper and lower edges of the plates 7 are clamped to the upper and lower heads through the medium of clamps 11 and clamping bolts 12. Each clamp 11 has two legs 13 resting against the outside of the plate 7 as is clearly seen in Fig. 2, and the corresponding clamping bolt extends through the clamp and screws into the head.

The upper head 2 has a fitting 14 secured thereto, which fitting is provided with an inlet passage 15 communicating with the inlet port 3. This fitting will be connected to a suitable inlet pipe for delivering to the passage 15 the pulp to be screened. 16 indicates a discharge pipe secured to the lower head 4 and communicating with the discharge opening 5, the screened pulp being delivered through said pipe 16.

Located within the casing 1 is a screening element presenting a vertical screening plate situated to intercept the pulp as it flows from the inlet to the discharge opening. In the illustrated embodiment of the invention the screening element is in the form of a vertically-arranged stationary cylinder 17 having perforated screening side walls and an upper head 18 and a lower head 19. The lower head 19 is formed with a central opening 20 which communicates with the discharge opening 5 through the lower head 4 of the casing. The screening element is stationarily mounted and the lower head 19 is formed with a flange portion 21 which engages the lower head 4 of the casing, the said screening element being clamped to the lower head of the casing by suitable tie rods 22 which are anchored at their upper ends in the upper head 18 of the screening element, and which extend through the lower head of the screening element and also through the lower head 4 of the casing, said tie rods having clamping nuts 23 thereon by which the screen-

ing element is clamped to the lower head of the casing.

The pulp to be screened flows into the casing 1 through the inlet 3 and through the stationary 5 cylindrical screening plate 17 into the interior of the screen and thence through the discharge openings 20 and 5.

Means are provided for causing the pulp to be forced back and forth through the screening plate 10 17 during its flow from the inlet to the discharge opening, the purpose of this pulsating movement of the pulp being to assist in keeping the screen free. The cylindrical screening plate 15 or wall 17 has rigid therewith a plurality of plates or partitions and between each two adjacent stationary plates is a movable plate or vane. Means are provided for vibrating the movable plates or 20 vanes between the stationary plates, thereby causing the pulp to be forced back and forth through the screening wall 17. In the embodiment 25 of the invention shown in Figs. 1, 2 and 3, the stationary plates or partitions are indicated at 24, said plates extending horizontally or transversely to the axis of the screening element, each plate or partition being in the form of a disc secured at its periphery to the wall 17 and provided with a central opening 25. These stationary partitions are held spaced from each other by spacing sleeves 33 which encircle the tie 30 rods 22 as shown in Fig. 7 and which pass through openings. The movable plates or vanes are in the form of disks which are indicated at 26 and these also extend horizontally and parallel to the plates or partitions 24 and each of which has 35 a central opening 85. The movable plates or vanes 26 are arranged for vertical movement, each plate or vane being movable between the two dotted line positions indicated at *a* and *b*. The movable plates or vanes 26 are carried on a vertical reciprocating spindle 27 which reciprocates 40 in two bearings 28, 29 carried by the lower and upper heads 19, 18 of the screening element. This spindle 27 has rigid therewith two sets of radial arms 30 and 31, the ends of the arms of each 45 set being bifurcated and receiving in the bifurcations one of the movable plates or vanes 26 as is best seen in Fig. 1. The movable vanes 26 are all rigidly connected by tie rods 32 and the adjacent plates or vanes are held properly spaced 50 by spacers 33 in the form of sleeves which encircle the tie rods 32. Since one of the movable plates 26 is anchored in the arms 30 and another of said plates is anchored in the arms 31, the said plates are not only rigidly connected by the tie rods 32 and spacers 33, but they are also rigidly 55 secured to the arms 30 and 31 which in turn are rigid with the vertical spindle 27. The spacing sleeves 33 extend through apertures 34 formed in the stationary plates or partitions 24. The movable plates 26 are provided with apertures 84 60 through which the spacing sleeves 33 extend as shown in Fig. 7.

Vertical reciprocating movement of the spindle 27 will, therefore, reciprocate the movable vanes 26 in a vertical direction, such reciprocation moving the vanes between the dotted line positions *a*, *b* as stated above.

The spindle 27 extends upwardly through the central or hub portion 34 of the fitting 14 and the upper end is connected by a connecting member 35 to an eccentric strap 36 which encircles an eccentric 37. This eccentric is mounted in suitable bearings in the fitting 14 and has rigid therewith a sprocket wheel 38 which is connected by 75 a sprocket 39 to a driving sprocket 40 on a shaft

41, the latter having a driving pulley 42 thereon by which it is operated.

The plates or vanes 26 are shown in full lines in Fig. 1 in approximately their central position, and as these plates or vanes are moved downwardly by the operation of the eccentric 35, the pulp between each movable vane and the stationary plate 24 directly below it will be forced outwardly through the screening wall 17, and as each movable plate or vane moves away from 10 the stationary partition above it the pulp will be drawn inwardly through the screening cylinder. When the plates or vanes 26 move upwardly the pulp between each plate or vane and the stationary partition 24 above said plate or vane will 15 be forced outwardly through the screening wall 17, while at the same time the pulp will be drawn inwardly through said wall into the space between the upwardly moving plate or vane and the stationary partition below it. Each moving 20 plate or vane, therefore, will cause a local pulsation or movement of the pulp back and forth through the screening cylinder 17, and hence there will be a plurality of such local movements throughout the vertical dimension of the 25 screening cylinder.

There will also be a general movement of the pulp through the casing 1 from the inlet passage 15 to the discharge pipe 16 and during this 30 forwardly flowing movement the pulp is repeatedly forced back and forth through the cylindrical screening wall 17. This operation serves to keep the exterior of the wall free and prevents it from becoming clogged either with the fibres in the pulp or with the refuse or rejects which 35 are being screened out from the pulp.

As a further means of keeping the screen free and preventing it from becoming clogged, I employ a plurality of cleaning runners which are located on the exterior of the cylindrical screen 40 adjacent the surface thereof and which are moved over the surface of the screen. These runners are indicated at 43, said runners preferably having the cross-sectional shape shown in Fig. 2, and each runner having an inclined or slightly 45 spiral shape. Each runner is connected at its lower end to a ring member 44 and at its upper end to another ring member 45, the runners preferably being integral with said ring members. The upper ring 45 is secured to the periphery of 50 a flange or plate 46 which is keyed to or otherwise made rigid with a sleeve 47 and this is journaled in the hub portion 34 of the fitting 14. The inner face 48 of the lower ring 44 encircles and bears on bearing rollers 49 which are secured to studs 50 that are anchored in the lower head 19 of the screening cylinder, these rollers 49 thus serving to center the ring 44.

Means are provided for rotating the sleeve 47 and flange 46, together with the runners connected thereto so that the runners are moved around the cylindrical surface of the screening cylinder 17. For this purpose the upper end of the sleeve 47 has a worm gear 51 fast thereon which meshes with a worm 52 on the shaft 41. 60 The runners 43 are shown as wedge-shaped in cross section (see Fig. 2) and the edge 53 of each runner lies closely adjacent the exterior surface of the screen cylinder 17. These wedge-shaped runners are arranged at an angle to a radial 70 direction so that the front or leading face 55 makes an obtuse angle with the outer face of the screen cylinder 17, while the rear or following face 56 makes an acute angle with said cylinder face. As the cleaning runners move around the 75

cylinder, each runner tends to remove from the exterior face of the screen cylinder any mass of fibres or refuse or dirt which is screened out of the pulp, thereby preventing the screen from becoming clogged. Because of the shape of the runners 43 and their angular relation to the exterior surface of the screening cylinder 17, the movement of each runner through the pulp will cause a suction at the rear face of the runner, and this suction tends to remove from the exterior face of the screen any dirt which may be accumulated thereon but which is not scraped off from the screen by the edge 53 of the runner. It will be noted that these edges 53 do not contact with the screen but are spaced slightly therefrom, and any dirt which accumulates on the outside of the screen but passes between the edge 53 and the runners will be loosened from the screen by the suction created at the rear face of each runner.

I propose to construct the means for vibrating the spindle 27 and for rotating the cleaning runners so that each runner will travel through the angular distance between adjacent runners during the movement of the movable plates or vanes 26 from their upper to their lower position or vice versa. Hence, any fibre mass or refuse which collects on the exterior of the screen plate during the pulsating movement of the pulp due to the downward movement of the plates or vanes 26 will be removed by the cleaning runners before the plates 26 are given their reverse or upward movement, and similarly any fibre mass or refuse which collects on the exterior of the screen plate during the upward movement of the vanes 26 and which would tend to clog the screen, will be removed by the cleaning runners 43 before the plates or vanes are again given their downward movement.

The flange 46 carrying the runners is shown as having openings 57 therein. As the unscreened pulp flows through the inlet port 3, the greater portion thereof will flow outwardly over the flange 46 and downwardly around the screen cylinder 17, said pulp gradually flowing through said screen cylinder 17, but at the same time being forced back and forth through the screening cylinder by the vertical vibration of the plates or vanes 26 as said pulp flows to the discharge opening.

Some of the pulp will flow through the apertures 57 into the space between the flange 46 and the head 18 of the screening cylinder, this pulp flowing around the head 18 and to the upper end of the cylinder.

The inlet 15 communicates with a tank or vat 80 to which pulp may be supplied from a supply pipe 81. The discharge pipe 16 leads to a delivery box 82 having a discharge 83, said delivery box 82 with its discharge being so situated relative to the supply box 80 that the level of the pulp in the delivery box or chest 82 will be slightly below the level of the unscreened pulp in the supply box or chest 80. This difference of level between the supply box or chest 80 and the delivery box or chest 82 provides the necessary head for causing the flow of the pulp through the screening cylinder. As a result of this arrangement, the casing 1 will always be kept filled with pulp and will have no air spaces therein.

The lower head 4 of the casing 1 is shown as having discharge openings 74 therein for the discharge of the rejects or refuse which is screened from the pulp. Suitable pipes 84 are connected to these discharge openings 74, and these pipes

will preferably be carried to a level substantially the same as that in the discharge chest 82, so that there will be the same head between the inlet chest 80 and the discharge end of the pipes 84 as between the inlet chest 80 and the discharge chest 82.

As the screening action takes place the refuse and other materials screened out of the pulp will be gradually worked down to the lower end of the casing 1 by the runners 43 and will then be discharged through the discharge openings 74 and discharge pipe 84.

17 indicate supporting feet secured to the lower head 4 and which rest on suitable supports 73.

In Figs. 4, 5 and 6 I have illustrated a different embodiment of the invention wherein the stationary and movable plates or vanes extend vertically instead of horizontally and the movable vanes have a horizontal vibrating movement. In the device shown in Fig. 4 the vat or casing 1 and the screening cylinder 17 are the same as above described with reference to Figs. 1, 2 and 3 except that the stationary partitions or plates which are rigid with the screening cylinder extend vertically and have a radial arrangement. These stationary plates are indicated at 58, each plate being rigidly secured at its outer edge 59 to the inner wall of the cylinder 17, and having its upper and lower edges engaging the upper and lower heads 18, 19 of the screen cylinder and clamped therebetween. The movable plates or vanes are indicated at 60, and these have a radial arrangement and are rigid with a sleeve or hub member 61 which is fast on a shaft 62 that is journaled at its lower end in the bearing 63 carried by the lower head 19 of the screening cylinder, and at its upper end in the bearing 64 carried by the upper head 18 of said screening cylinder. This shaft 62 is given an oscillating movement whereby to oscillate the plates 60 between the dotted line positions c, d (see Fig. 5). This oscillating movement of the plates 60 has the same effect in causing local pulsation of the pulp as the vertical vibrating movement of the plates or vanes 26 in Fig. 1. The means for vibrating the plates 60 and for rotating the cleaning runners 43 is best shown in Fig. 6. The upper end of the shaft 62 has an arm 65 rigid therewith which is pivotally-connected to a connecting member 66 extending from an eccentric strap 67 that encircles an eccentric 68 formed on a shaft 69. The shaft 69 is provided with a driving pulley 70 by which it is rotated and as the shaft rotates the eccentric 68 and connections 66, 65 produce the necessary oscillating movement in the shaft 62 to cause the plates 60 to move between the dotted line positions c, d.

The shaft 69 has a gear 71 thereon meshing with a gear 72 which is secured to the upper end of the sleeve 47 which carries the cleaning runners. The gearing for rotating the runners and for vibrating the shaft 62 will preferably be so constructed that each runner will move through the angular distance between adjacent runners, while each plate 60 is moving from one to the other dotted line position.

The device shown in Figs. 4 to 6 operates in the same manner as that described in Figs. 1 to 3 except that the local pulsations of the pulp are in zones extending vertically of the screening cylinder, rather than in zones extending circumferentially thereof as is the case in the construction shown in Fig. 1.

I claim:

1. A pulp screening machine comprising a cas-

75

ing having an inlet at its upper end and a discharge opening at its lower end; a screen element situated within the casing between the inlet and the discharge opening and having a vertical screening wall, means for forcing the pulp back and forth through the screening wall as said pulp flows from the inlet to the discharge opening, screen-cleaning runners on the inlet side of the screening wall and means to produce a relative movement between said runners and said wall.

2. A pulp screening machine comprising a casing having an inlet at its upper end and a discharge opening at its lower end, a screen element situated within the casing between the inlet and the discharge opening and having a vertical screening wall, means for forcing the pulp back and forth through the screening wall as said pulp flows from the inlet to the discharge opening, screen-cleaning runners on the inlet side of the screening wall and means to move the screen-cleaning runners relative to the screening wall.

3. A pulp screening device comprising a casing having an inlet at its upper end and a discharge opening at its lower end, a screening element within the casing having a vertical cylindrical screening wall, means for forcing the pulp back and forth through the cylindrical screening wall as it flows from the inlet to the discharge opening, screen-cleaning runners on the exterior of the screening wall and means to produce a relative movement between said runners and said cylindrical wall.

4. A pulp screening device comprising a casing having an inlet at its upper end and a discharge opening at its lower end, a screening element within the casing having a vertical cylindrical screening wall, means for forcing the pulp back and forth through the cylindrical screening wall as it flows from the inlet to the discharge opening, screen-cleaning runners on the exterior of the screening wall and means to cause the screen-cleaning runners to rotate around the cylindrical screening wall.

5. A pulp screening apparatus comprising a casing having an inlet at its upper end and a discharge opening at its lower end, a screening element within the casing having a vertical cylindrical screening wall situated between the inlet and the discharge opening, a plurality of plates or partitions within the cylindrical screening wall and rigid therewith, movable plates or vanes situated between the partitions and means to vibrate the movable plates toward and from the stationary partitions thereby causing the pulp to be forced back and forth through the cylindrical screening wall as it flows from the inlet to the discharge opening.

6. A pulp screening apparatus comprising a casing having an inlet at its upper end and a discharge opening at its lower end, a screening element within the casing having a vertical cylindrical screening wall situated between the inlet and the discharge opening, a plurality of plates or partitions within the cylindrical screening wall and rigid therewith, movable plates or vanes situated between the partitions, means to vibrate the

movable plates toward and from the stationary partitions thereby causing the pulp to be forced back and forth through the cylindrical screening wall as it flows from the inlet to the discharge opening, a plurality of screening runners located on the exterior of the cylindrical screening wall in close adjacency thereto and means to rotate the runners about said screening wall.

7. A pulp screening machine comprising a casing having an inlet at its upper end and a discharge opening at its lower end, a vertically-arranged screen plate situated within the casing between the inlet and the discharge opening, means for forcing the pulp back and forth through the screen plate as said pulp flows from the inlet to the discharge opening, screen-cleaning runners on the inlet side of the screen plate, means to produce a relative movement between the runners and the plate and discharge openings in the bottom of the casing on the inlet side of the screen plate for the discharge of rejects.

8. A pulp screening machine comprising a casing having an inlet at its upper end and a discharge opening at its lower end, a vertically-arranged screen plate situated within the casing between the inlet and the discharge opening, means for forcing the pulp back and forth through the screen plate as the pulp flows from the inlet to the discharge opening, an inlet chest communicating with the inlet opening and from which pulp is supplied thereto and a discharge conduit connecting to the discharge opening of the casing and leading to the level slightly below that of the pulp supplied to said inlet opening.

9. A pulp screening machine comprising a casing having an inlet at its upper end and a discharge opening at its lower end, a vertically-arranged screen plate situated within the casing between the inlet and the discharge opening, means for forcing the pulp back and forth through the screen plate as the pulp flows from the inlet to the discharge opening, an inlet chest communicating with the inlet opening and from which pulp is supplied thereto and a discharge chest having an outlet slightly below the level of the pulp in the supply chest and a discharge pipe connecting the discharge opening of the casing with said discharge chest.

10. A pulp screening machine comprising a casing having an inlet at its upper end and a discharge opening at its lower end, a vertically-arranged screen plate situated within the casing between the inlet and the discharge opening, means for forcing the pulp back and forth through the screen plate as the pulp flows from the inlet to the discharge opening, an inlet chest communicating with the inlet opening and from which pulp is supplied thereto and a discharge conduit connecting to the discharge opening of the casing and leading to the level slightly below that of the pulp supplied to said inlet opening, said casing having in its bottom a discharge opening for rejects on the supply side of the screen plate and a discharge pipe connected to said latter discharge opening and leading to a level slightly below the pulp level in the supply chest.

NELSON MOORE KNIGHT.
